(57) **CLAIM**

I claim the ornamental design for a vehicle door, as shown and described.

DESCRIPTION

FIG. 1 is a front view of a vehicle door, showing my new design.

FIG. 2 is a left side perspective view thereof.

FIG. 3 is a left side view thereof.

FIG. 4 is a top view thereof.

FIG. 5 is a right side perspective view thereof.

FIG. 6 is a right side view thereof.

FIG. 7 is a rear view thereof; and,

FIG. 8 is a bottom view thereof.

The broken lines and lightened elements within, illustrate portions of the vehicle door which form no part of the claimed design.

1 Claim, 8 Drawing Sheets
